TOY POWER LAWN MOWER

Robert N. Lesnick, Franklin Township, Beaver County,
Pa., assignor to Roberts Manufacturing Company, Ell-
wood City, Pa., a corporation of Pennsylvania

Application December 23, 1953, Serial No. 28,184

Term of patent 14 years

(Cl. D34—16)

FIG. 1.

FIG. 2.

Des. 173,760

PAGE 2

FIG. 5.

To all whom it may concern:

Be it known that I, Robert N. Lesnick, a citizen of the United States, residing at Franklin Township, in the county of Beaver, Commonwealth of Pennsylvania, have invented a new, original, and ornamental Design for a Toy Power Lawn Mower, of which the following is a specification, reference being had to the accompanying drawings, forming a part thereof.

Fig. 1 is a top plan view of a toy power lawn mower, showing my new design;

Fig. 2 is a left side elevation thereof;

Fig. 3 is a right side elevation thereof;

Fig. 4 is a front elevation thereof;

Fig. 5 is a rear elevation thereof.

I claim:
The ornamental design for a toy power lawn mower, as shown.
